Patented Dec. 31, 1963

197,231

KNOB FOR STEREO AMPLIFIERS OR THE LIKE

Victor H. Pomper, 3 Lexington Road, Concord, Mass.

Filed Aug. 16, 1963, Ser. No. 76,237

Term of patent 14 years

(Cl. D26—13)

FIG.2

FIG.1

FIG.3

FIG. 1 is a side elevational view of a knob for stereo amplifiers or the like showing my new design;

FIG. 2 is a top view of the knob in FIG. 1; and

FIG. 3 is a bottom view of the knob in FIG. 1.

I claim:

The ornamental design for a knob for stereo amplifiers or the like, substantially as shown.
